UNITED STATES PATENT OFFICE

107,419

DESIGN FOR A TRANSPLANTING TOOL

George W. Gasser, College, Territory of Alaska

Application July 12, 1937, Serial No. 70,380

Term of patent 3½ years

To all whom it may concern:

Be it known that I, George W. Gasser, a citizen of the United States, residing at College, in the Territory of Alaska, have invented a new, original, and ornamental Design for a Transplanting Tool, of which the following is a specification, reference being had to the accompanying drawing, forming part thereof.

Figure 1 is a view in side elevation of a transplanting tool, showing my new design.

Figure 2 is a view in elevation thereof, taken at right angles to Fig. 1.

I claim:—

The ornamental design for a transplanting tool as shown.

G. W. GASSER.
